SUPPORT FIXTURE FOR SUPPORTING
PRONGED STRUCTURESCharles W. Daley, Indianapolis, Ind., assignor to
Radio Corporation of America, a corporation
of Delaware

Application June 28, 1950; Serial No. 170,829

6 Claims. (Cl. 49—2)

1

My invention relates to a novel support fixture for supporting a pronged structure, and more particularly concerns a head or pin for supporting an electron tube component such as a flat glass stem having lead-ins extending therefrom, on an apparatus for processing electron tubes.

One type of apparatus employed in processing electron tubes comprises a machine for sealing a tubular glass envelope portion of an electron tube to a flat, button type glass stem having lead-ends extending from both faces thereof. The lead-ins extending from one face of the stem serve to support an electrode assembly and the lead-ins extending from the other face serve as contact prongs for the finished tube.

The apparatus referred to includes an intermittently rotatable turret having adjacent its periphery a plurality of heads or pins for supporting the stems referred to, during the sealing operation. The pins are provided with upper flat surfaces lying in horizontal planes and have bores or holes extending vertically downward from said surfaces. The bores or holes in each of the pins are arrayed in a pattern similar to the array of the contact prongs on a stem, for receiving said prongs. This array, for example, may be circular. When the prongs of a stem are received in the bores referred to, the flat stem rests on the upper surface of a pin. This is the desired position of a stem for sealing thereto a glass envelope.

One of the difficulties encountered in processing electron tubes by an apparatus of the type described, resides in mounting the stem on the sealing pin. The bores in the sealing pins have heretofore been made with a diameter for receiving the prongs of the stem in substantially snug fits. This has required the operator of the machine to locate the stem properly in relation to all the bores in a pin to assure entrance of all the prongs in the bores. The operation of mounting a stem on a head or pin of an electron tube sealing machine has therefore required appreciable time and has contributed to substantial fatigue on the part of the operator.

It is therefore an object of my invention to facilitate the mounting of work pieces on an electron tube processing apparatus.

A further object of the invention is to provide an improved electron tube processing apparatus on which work pieces can be quickly and easily loaded.

Another object is to provide a support pin for an electron tube processing apparatus for quick-

ly and easily receiving a work piece to be processed.

A further object is to provide a sealing pin for an apparatus for sealing a glass stem to a glass envelope in the fabrication of an electron tube, wherein the mounting of the stem on the sealing pin is facilitated.

Another object is to provide a stem support fixture having an array of bores therein for facilitating entrance of prongs of said stem into said bores.

A further object is to provide a support fixture for a pronged flat stem wherein bores in said fixture for receiving prongs of said stem are dimensioned and arrayed for facile receipt of said prongs.

Another object is to provide a stem support fixture having a plurality of bores therein for receiving prongs extending from said stem without requiring critical registry between all of said bores and said prongs when mounting said stem on said fixture.

A further object is to provide a fixture having bores therein for receiving and supporting a flat stem having prongs, wherein one of said bores is critically dimensioned for receiving one of said prongs in a snug fit and the other bores are dimensioned for quick and easy receipt of the other of said prongs.

One embodiment of the invention attaining the foregoing objects may be a vertically disposed head or pin having an upper flat surface provided with a plurality of bores or holes disposed in a partly circular array for receiving and supporting a flat glass stem having a circular array of prongs extending therefrom. The prongs of the stem may be of equal diameter. One of the bores referred to has a diameter for receiving one of the prongs in a relatively snug fit. The other bores have diameters substantially greater than the diameter of the prongs. The array of the bores is such that when all the prongs are received therein, one of the prongs fits tightly in one of the bores and the other prongs engage the walls of the bores adjacent the inner edge of the array of bores.

This novel arrangement and dimension of the bores in the pin facilitates mounting a stem on the pin, and assures that after all the prongs are extended into the bores, the stem is critically positioned on the pin for processing by the apparatus of which the pin is a part.

While the invention is pointed out with particularity in the appended claims, it may best be understood from a consideration of the fol-

3

lowing detailed description of an embodiment thereof presented for illustration only, taken in connection with the appended drawing:

Figure 1 is a perspective view of a support fixture and a flat glass stem having lead-ins extending therefrom and adapted to be supported on the fixture;

Figure 2 is a side view of the support fixture with the stem in supported position thereon;

Figure 3 is a cross-section along the line 3—3 of Figure 2, and shows the array and dimensions of the bores in the support fixture in relation to the lead-ins or prongs extending from one face of the stem; and

Figure 4 is an elevation in section along the line 4—4 of Figure 2, and depicts the snug fit of one of the prongs of the stem in one of the bores of the support fixture, and the loose fit of another prong in another bore.

Referring now in more detail to the drawing, there is shown in Figure 1 a support fixture 10 which may be a head or a sealing pin of a glass sealing apparatus, not shown. The fixture has an upper horizontal surface 11 from which a plurality of bores 12 to 19, inclusive, extend downwardly in a vertical direction. The surface 11 of the pin is adapted to receive a flat glass stem 20. The glass stem 20 has lead-ins 21 extending from the upper face thereof and adapted to be connected to an electrode assembly, not shown. The stem 20 also has prongs 22 extending from the other face thereof and electrically connected to the lead-ins referred to.

One general use of pins or heads of the type discussed is on sealing machines of the turret type for sealing a glass stem having an electrode assembly mounted thereon, to a glass envelope to form an electron tube. These machines rotate in intermittent movements to carry the heads successively through a plurality of processing stations including a loading station. The heads are held stationary for a relatively short interval at each of the stations referred to.

In view of the relatively short interval during which a head is stationary at the loading station, it is necessary that the operation of loading a stem having lead-ins extending therefrom on a head of the machine be performed quickly. The loading operation on conventional machines requires that the stem be first oriented above a pin so that the prongs of the stem are in registry with the bores in the pin, and then be pushed downwardly on the pin without disturbing the orientation referred to so that the prongs enter the bores. This operation is difficult to perform and generally requires a number of trials and errors before the stem is properly mounted or loaded on the pin. Since the trial and error method of loading must be carried out during the relatively short interval when a pin is stationary at the loading station, it is necessary that the operator work fast with a consequent increase in fatigue.

The novel sealing pin according to the invention eliminates the need for a plurality of trials before a stem is properly fitted on a pin.

According to the invention, the pin is provided with a plurality of bores extending downwardly from an upper surface thereof and disposed in a predetermined array, so that when the prongs 22 of the stem 20 are in registry with the bores, only one of the prongs is coaxial with a bore 12. The other bores 13 to 19, inclusive, are appreciably wider than the prongs and are arranged in such a manner that the prongs 22 other than the prong entering bore 12, are in registry with

4

portions of the bores adjacent the inner edge of the array. Thus, while the bores 13 to 19 are seemingly wide enough to permit free play therein of prongs, such free play is permitted only prior to engagement of all the prongs with all the bores in the pin. After this engagement is completed, the stem is held in a predetermined fixed position on the pin with no play permitted between the prongs and the walls of the bores.

It will be noted from Figure 3, that the prongs 22 are in a circular array, the axes of the prongs defining a circle 23 shown in dotted line. The sides of the prongs facing inwardly of this array also define a circle 24 shown in dotted line. Circle 24 is of smaller diameter than the circle 23. The difference in diameter between circles 23 and 24 is equal to the diameter of a prong 22. While the axis of bore or hole 12 is included in the circle 23, the axes of the other bores 13 to 19 define a circle 25 having a larger diameter than circle 23. It will be noted that circle 25 is concentric with circles 23 and 24.

The arrangement and size distribution of the bores referred to facilitates loading a stem on a pin. The operation of loading involves first extending a prong into bore 12, and then rotating the stem on this prong without disturbing the engagement between the prong and the bore 12, until the other prongs enter the bores 13 to 19. To further facilitate entrance of the other prongs referred to into their associated bores, it is helpful to tilt the stem slightly to the left or right as viewed in Figure 1 after bore 12 is engaged by a prong to initially engage the wider bores disposed to one side of the pin. This engagement need not be critical and is therefore quickly performed. Once the prongs to either the left or right of the stem are engaged by bores in the stem, all that remains is for the operator to rotate the stem in the opposite direction that in which the engaged bores lie. This will bring engaged prongs into contact with the walls of the bores adjacent the inner edge of the bore array and will result in registry between the other prongs and bores. The stem is then simply pushed down on the pin and all the prongs of the stem enter the bores in the pin.

An alternative procedure for loading a stem on a pin that is rendered available by my invention involves first, extending a prong into one of the wider bores and then urging the stem toward the center of the bore array. This automatically brings the other pins into registry with the other bores. A further modification in procedure is to first extend as many prongs as readily feasible into the wider bores and then insert the final prong into the narrower bore. The preferable practice is first to engage one or more of the prongs in the wide bores and then complete the mounting operation by urging the stem to the center of the pin to secure registry between the reaming bores and prongs.

The pin of the invention therefore permits a loading operation of positive steps requiring no repetition for trial purposes.

Once a suitable sequence of steps as described above has been learned by an operator, the loading of a stem on a pin can be accomplished quickly and with a minimum of fatigue on the part of the operator.

The increased rapidity of loading stems on a sealing machine that my invention accomplishes is of particular significance in view of the present trend toward increased speed of operation of electron tube processing machines. In many in-

stances the loading operation is the only manually performed step and accordingly represents the operation least quickly performed during operation of the machine. Increasing the speed of loading therefore permits many types of machines to be operated faster with consequent increase in output and reduced cost per unit processed.

Various modifications in the embodiment described will suggest themselves to persons skilled in the art without departing from the invention. For example, the invention may be incorporated in sockets for receiving pronged members wherein the socket is an independent support fixture and not associated with a machine. Accordingly it is desired to include such modifications within the scope of the appended claims.

I claim:

1. A fixture for an electron tube processing machine adapted to receive a flat glass stem having prongs of equal diameter extending from one face of the stem and having axes disposed in a circular array, said fixture having a surface adapted to receive said glass stem, said surface having bores therein adapted to receive said prongs, one of said bores having a predetermined diameter and adapted to receive one of said prongs in a snug fit and having an axis disposed in said array, the others of said bores having diameters larger than said predetermined diameter and adapted to receive the others of said prongs in loose fits and having axes disposed in a circular array concentric with and of larger radius than said first named circular array, said others of said bores being defined by walls having portions adapted to contact said others of said prongs, whereby the mounting of said stem on said fixture is facilitated.

2. A socket fixture for an electron tube processing machine adapted to receive in mounted position thereon a flat glass stem having prongs of equal diameter extending from one face thereof in a circular array, said fixture having bores therein adapted to receive said prongs, one of said bores having a smaller diameter than the others of said bores, all of said bores being tangent to a circle concentric with said circular array and having a smaller diameter than said array whereby said one of said bores is adapted to receive snugly one of said prongs and to serve as a locating means for initially locating said stem on said fixture and said others of said bores are adapted to receive the others of said prongs by rotating said stem on said one of said prongs for registry with said others of said bores.

3. A socket fixture for an electron tube processing machine adapted to receive in mounted relation thereon a flat glass electron tube stem having prongs of equal diameter extending from one face of the stem and disposed in a closed array, surfaces of said prongs inwardly of said array being in a circular array, said fixture having a surface adapted to engage said one face of the stem, said surface having bores therein adapted to receive said prongs, one of said bores having a diameter substantially equal to that of one of said prongs, the others of said bores having a larger diameter than any one of said prongs, said bores being disposed in a closed array and having edges inwardly of said array disposed in a cir-

cular array concentric with and having a diameter equal to said first-named circular array, whereby mounting of said prongs in said bores is facilitated.

- 5 4. A socket adapted to receive prongs of equal diameter having axes in a circular array, said socket having holes arranged in a closed array for reception of said prongs, one of said holes having its axis in said circular array and being of the same diameter as said prongs, the remainder of the holes having a larger diameter than said prongs and having axes disposed in a circular array concentric with and of slightly larger diameter than the circular array of said prongs, 10 all of said holes being tangent to a circle concentric with and of smaller diameter than the diameter of said first named circular array, whereby extension of said prongs into said holes is facilitated.
- 15 5. A socket having holes arranged to receive circularly arranged and equal diameter prongs, said holes being disposed in a closed array and defined by walls including portions facing inwardly of said array, said portions being arranged to define a circle concentric with and having a diameter smaller than the diameter of the circular array of said prongs, said last named diameter being substantially equal to the sum of the diameter of said circle and a diameter of 20 one of said prongs, one of said holes being substantially of the diameter of said prongs, the remainder of said holes having a larger diameter than said prongs, whereby extension of said prongs into said holes is favored.
- 25 6. A socket for an electron tube processing machine, said socket having a flat surface adapted to receive a flat glass stem, said surface having bores therein for receiving prongs of equal diameter disposed in a circular array and extending from one face of said stem, one of said bores having a predetermined diameter, whereby said one of said bores is adapted to receive initially one of said prongs in a snug fit, the others of said bores having larger diameters than said 30 predetermined diameter, said bores being disposed in a closed array on said surface, said others of said bores having axes disposed in a circle in said closed array having a larger diameter than and concentric with said circular array of the prongs, all of said bores being tangent to a circle defined by surfaces of said prongs facing inwardly of said circular array of the prongs, whereby said others of said bores are adapted to receive the others of said prongs with 35 reduced attention to registry between said last named bores and prongs.
- 40 7. A socket for an electron tube processing machine, said socket having a flat surface adapted to receive a flat glass stem, said surface having bores therein for receiving prongs of equal diameter disposed in a circular array and extending from one face of said stem, one of said bores having a predetermined diameter, whereby said one of said bores is adapted to receive initially one of said prongs in a snug fit, the others of said bores having larger diameters than said predetermined diameter, said bores being disposed in a closed array on said surface, said others of said bores having axes disposed in a circle in said closed array having a larger diameter than and concentric with said circular array of the prongs, all of said bores being tangent to a circle defined by surfaces of said prongs facing inwardly of said circular array of the prongs, whereby said others of said bores are adapted to receive the others of said prongs with 45 reduced attention to registry between said last named bores and prongs.
- 45 8. A socket for an electron tube processing machine, said socket having a flat surface adapted to receive a flat glass stem, said surface having bores therein for receiving prongs of equal diameter disposed in a circular array and extending from one face of said stem, one of said bores having a predetermined diameter, whereby said one of said bores is adapted to receive initially one of said prongs in a snug fit, the others of said bores having larger diameters than said predetermined diameter, said bores being disposed in a closed array on said surface, said others of said bores having axes disposed in a circle in said closed array having a larger diameter than and concentric with said circular array of the prongs, all of said bores being tangent to a circle defined by surfaces of said prongs facing inwardly of said circular array of the prongs, whereby said others of said bores are adapted to receive the others of said prongs with 50 reduced attention to registry between said last named bores and prongs.
- 55 9. A socket for an electron tube processing machine, said socket having a flat surface adapted to receive a flat glass stem, said surface having bores therein for receiving prongs of equal diameter disposed in a circular array and extending from one face of said stem, one of said bores having a predetermined diameter, whereby said one of said bores is adapted to receive initially one of said prongs in a snug fit, the others of said bores having larger diameters than said predetermined diameter, said bores being disposed in a closed array on said surface, said others of said bores having axes disposed in a circle in said closed array having a larger diameter than and concentric with said circular array of the prongs, all of said bores being tangent to a circle defined by surfaces of said prongs facing inwardly of said circular array of the prongs, whereby said others of said bores are adapted to receive the others of said prongs with 55 reduced attention to registry between said last named bores and prongs.
